UNITED STATES PATENT OFFICE.

WILLIAM C. ANTHONY, OF STREATOR, ILLINOIS, ASSIGNOR TO ANTHONY COMPANY, OF STREATOR, ILLINOIS, A CORPORATION OF ILLINOIS.

BODY SUPPORT AND LOCK.

1,392,615.

Specification of Letters Patent. Patented Oct. 4, 1921.

Application filed April 17, 1920. Serial No. 374,558.

To all whom it may concern:

Be it known that I, WILLIAM C. ANTHONY, a citizen of the United States, residing at Streator, in the county of La Salle and State 5 of Illinois, have invented a certain new and useful Improvement in Body Supports and Locks, of which the following is a specification.

My invention relates to dumping bodies 10 for vehicles and the like and primarily to supporting and locking mechanisms for the same. One object of my invention is to provide a mechanism which will support and lock the body in the horizontal position. 15 Another object of my invention is to provide a mechanism for supporting the body in the tilted or dumping position. Other objects of my invention will appear from time to time throughout the specification 20 and claims.

My invention is illustrated more or less diagrammatically wherein:

Figure 1 is a side elevation of my body in the horizontal position; 25 Fig. 2 is a similar view with the body in the dumping position.

Fig. 3 is a vertical section on the line 3 3 of Fig. 1;

Fig. 4 is a section on the line 4 4 of Fig. 2; 30 Fig. 5 is a section of Fig. 4 at line 5 5 on an enlarged scale;

Fig. 6 is a vertical section on line 6 6 of Fig. 3;

Fig. 7 is a horizontal section on line 7 7 of 35 Fig. 3.

Like parts are indicated by like characters throughout.

A is the frame of a truck. B is the running gear. C is a rack mounted on said truck frame and adapted to coöperate with the cam C¹ which is secured to the bottom of the body frame C² upon which is mounted the body C³. C⁴ is an eccentrically hung tail gate. C⁵ is a rod mounted for rotation 40 in the rear of the body frame carrying the hooks C⁶—C⁸ adapted to hold the tail gate closed. C⁹ is an arm mounted on the shaft C⁵ and adapted to contact a part of the running gear of the truck to open the tail gate 45

automatically when the body has reached 50 the proper inclination. C⁹ is a lever arm mounted on the shaft C⁵ connected by the rod C⁹ to the lever arm C¹⁰ by means of which the tail gate may be opened manually at the will of the operator. 55

D is a subdividing gate removably mounted within the body on the bearings D¹—D¹. It is eccentrically hung on the rod D² and is adapted to be opened by the lever D³. D⁴ is a counterweight which causes the rod D² 60 to rotate in a direction opposite from which it has been pulled by the operator. D⁵ is a chain fastened to the upper end of the lever D³ by means of which the operator may open the gate D at will. 65

E is an A-shaped frame support for the forward end of the body. It is secured to the upper flange A¹ of the channel section of the truck frame A. The extensions E¹—E¹ of the frame E rest on the upper surface of 70 the truck frame. The lugs E²—E² project under the flanges A¹—A¹ and are screw threaded for the set screws E³—E³ which bear against the lower surface of the flanges A¹—A¹, thus securing the frame E to the 75 truck frame. E⁴—E⁴ are U bolts passing through the extensions E¹—E¹ of the frame E and about the truck frame members A—A. E⁵—E⁶ are ears projecting from the extensions E¹—E¹ and perforated to receive 80 the ends of the chains F—F. The upper surface of the frame E is provided with the lug E⁶.

G is a locking and controlling lever pivoted at G¹ on the frame E and provided 85 with the upper extension G² adapted for use as a controlling handle. G³ is a lateral web on the handle G and carries on its lower surface the raised portion G⁴. G⁵ is an arc guide secured in the handle G and projecting through a hole G¹¹ in the frame E. G⁶ is a stop on the member G⁵. G⁸ is a spring bearing against the frame E and adapted 90 normally to hold the handle G in the position shown in Fig. 6. G⁹ is a lateral projection from the web G³ and is perforated at G¹⁰. 95

H is a hook receiving member secured to

the forward angle of the body frame C². It is provided with the forward horizontal extension H¹ which carries in its upper surface the raised portion H² adapted to co-operate with the similar raised portion G⁴ in the lower surface of the web G³. H³ is in an extension from the part H¹ perforated at H⁴ and adapted to fall beneath the perforation G¹⁰ of the part G⁹ when the parts are 10 in the position shown in Figs. 1, 3, 6, and 7.

I is a pin adapted to penetrate and lie within the two holes. I¹ is a chain by means of which the pin I is controlled. H⁵ is a pocket in the rear of the member H into which the lug E⁶ is adapted to penetrate.

J is a prop mounted on the truck frame at J¹—J¹ for rotation and in its upper end carries the hook J² which is provided with the raised portion J³ and the upper extension or handle J⁴ by means of which the prop may be withdrawn from the body when it is desired to let the body return to the horizontal position.

K is a recess on the under surface of the projection H¹ of the member H which is adapted to co-operate with the part J³ of the hook J² to keep the prop in the position shown in Fig. 2, and to prevent the parts from accidentally slipping out of contact.

L—L are springs fastened to the chains F—F and adapted to co-operate with them to cushion the shock as the body moves from the horizontal to the dumping position.

The use and operation of my invention are 35 as follows:

Normally, when the body is being loaded and until it is desired to dump it the relation of the parts is that shown in Fig. 1. The forward end of the body with the load 40 in it rests upon the A-shaped frame and the lug in that frame projects into the pocket in the member H thus preventing lateral displacement of the parts. The handle which is pivoted to the A frame is pulled 45 toward the body by its spring so that the web extending rearwardly from the handle overlaps the portion H¹ and the raised surfaces on the two co-operate to prevent lateral displacement. The web of the handle 50 of course prevents the body from tipping so long as the relation of the parts is that shown in Fig. 6 or Fig. 1. In order to provide against any accidental displacement of parts these two co-operating members, that

55 is the web on the handle and the web extending forward from the body frame, are both perforated and a pin is dropped into the perforations. In this position the body may be loaded and driven about to the place 60 where it is desired to dump the load.

While the body is in the horizontal position the prop J rests against its forward end. Automatically it will rest in that position by means of gravity alone. In some

situations it might be desirable to provide 65 a spring J⁵ to pull this prop rearwardly.

When it is desired to dump the body the pin which holds the webs in fixed relation is removed. The locking handle is moved forward and the body being free from the 70 web on the handle, tips and the rear tail

gate is opened either automatically or at the will of the operator. When this takes place the rear portion of the load will of

course be discharged and the forward portion of the load which is held in place by the dividing gate would ordinarily cause the body to return again to the horizontal position, and would thus make impossible a 75 further automatic discharge of that portion 80 of the load.

In order to prevent this and to maintain the body in the tilted position until such time as it is desirable to dump the remainder of the load, I provide the body prop above mentioned. As the body 85 moves to the dumping position this prop is held against it and when the body has

reached a sufficient inclination the hook on the end of the prop falls into place and remaining there holds the body in the position shown in Fig. 2, even after the discharge of the rearward portion of the load.

When now it becomes desirable to dump the remainder of the load, the subdividing gate is opened and when the load has been discharged the body prop is pulled out from 90 under the body and the body automatically 95 returns to the horizontal position and both of the gates are automatically closed. The

position of the parts is then again that shown 100 in Fig. 1 and as a precautionary measure the pin is again put in place as indicated in Fig. 3.

It will be understood that many changes might be made in the form and dimensions 105 of the parts shown, for example, the spring adapted to pull the body prop into position might be omitted; the springs adapted to cushion the rearward movement of the body might be omitted; the pin adapted to fasten the locking members together might be omitted.

These, and many other changes might be made both in size and arrangement of parts without materially departing from the spirit of my invention. I wish, therefore, 115 that my showing be regarded as in a sense diagrammatic.

I claim—

1. The combination with a vehicle of a dumping body mounted thereon and adapted 120 to be tipped with relation thereto, of a locking and supporting assembly adapted to lock and support the body in the untipped position and to support the body in the tipped position, said assembly including a pivoted 125 locking member adapted normally to hold the body in the untipped position, and a second pivoted member adapted to support

- the body in the tipped position, each of said pivoted members mounted upon said vehicle alone.
2. The combination with a vehicle of a dumping body mounted thereon and adapted to be tipped with relation thereto, of a locking and supporting assembly adapted to lock and support the body in the untipped position and to support the body in the 10 tipped position, said assembly including a pivoted locking member adapted normally to hold the body in the untipped position, and a second pivoted member adapted to support the body in the tipped position, each 15 of said pivoted members mounted upon said vehicle, and in combination with said first locking member, an additional safety locking member.
3. The combination with a vehicle of a 20 dumping body mounted thereon and adapted to be tipped with relation thereto, of a locking and supporting assembly adapted to lock and support the body in the tipped and the untipped position, said assembly including a fixed support for the untipped position, and a locking part fixed to said body and a locking handle pivoted on said fixed support and adapted to coöperate with the locking member on said body to hold the 25 body in the untipped position.
4. The combination with a vehicle of a 30 dumping body mounted thereon and adapted to be tipped with relation thereto, of a locking and supporting assembly adapted to lock and support the body in the tipped and the 35 untipped position, said assembly including a fixed support for the untipped position, a locking part fixed to said body and a locking handle pivoted on said fixed support and 40 adapted to coöperate with the locking member on said body to hold the body in the untipped position, and a spring adapted normally to hold said locking handle in the locking position.
5. The combination with a vehicle of a 45 dumping body mounted thereon and adapted to be tipped with relation thereto, of a locking and supporting assembly adapted to lock and support the body in the tipped and the 50 untipped position, said assembly including a fixed support for the untipped position, a locking part fixed to said body and a locking handle pivoted on said fixed support and adapted to coöperate with the locking member on said body to hold the body in the 55 untipped position, and a spring adapted normally to hold said locking handle in the locking position, and a perforation in the locking member on said body and in said 60 locking handle, said perforations adapted to overlie each other when the body is in the untipped position, and a pin adapted to penetrate said perforations and to lock the body against movement.
6. The combination with a vehicle of a 65 dumping body mounted thereon and adapted to be tipped with relation thereto, of a locking and supporting assembly adapted to lock and support the body in the tipped and the 70 untipped position, said assembly including a fixed support for the untipped position, said supporting member detachably mounted on and extending above said vehicle.
7. The combination with a vehicle having a channel section frame of a body mounted 75 on said frame and adapted to tip with relation thereto, of a locking and supporting assembly mounted on said frame and adapted to lock and support said body in a horizontal or tipped position, said assembly including a fixed supporting member adapted to support said body in the untipped position, said member adapted to grip the channel section of said vehicle frame on its 80 upper and lower surfaces.
8. The combination with a vehicle having a channel section frame, of a body mounted on said frame and adapted to tip with relation thereto, of a locking and supporting assembly mounted on said frame and adapted to lock and support said body in a horizontal or tipped position, said assembly including a fixed supporting member adapted to support said body in the untipped position, said member adapted to grip the channel section of said vehicle frame on its 85 upper and lower surfaces, and additional means for securing said member to said frame comprising means encircling said frame.
9. A supporting and locking means for a 90 tipping vehicle body comprising a locking member secured to said body, said member having in its under side a pocket and a laterally projecting perforated portion, a supporting member on said vehicle adapted to contact said locking member, a projection in the upper surface of said supporting member adapted to penetrate within the pocket in the under side of said locking member, a 95 locking handle pivoted on said supporting member and adapted to engage the upper surface of said locking member, a lateral projection from said locking handle adapted to overlie the lateral projection of said locking member and perforated to correspond to the perforation in said member, a spring adapted normally to hold said locking handle in the locking position and a pin adapted to project through said perforations.
10. A supporting and locking means for a 100 dumping vehicle body comprising a locking member on said body, said member provided on its under surface with a depression, a projection and a perforation, a pivoted 105 supporting and locking member on said vehicle, said member provided at its upper end with a hook adapted to contact the under

surface of said locking member and to penetrate within the depression thereof, a controlling handle attached to said supporting member.

5 11. The combination with a vehicle and a dumping body mounted thereon and adapted to tip with relation thereto, of a checking mechanism adapted to cushion the shock of the tipping of said body, said mechanism comprising one or more chains secured at

one end to said vehicle and at the other to said body, and a spring secured at one end to said body at a point distant from the end of said chain and at the other end to a point intermediate the ends of said chain. 15

Signed at Streator, county of La Salle and State of Illinois, this 14th day of April, 1920.

WM. C. ANTHONY.
